UNITED STATES PATENT OFFICE.

JAMES V. ANDERSON, OF CLARKSON, NEBRASKA.

WIRE-STRETCHER.

SPECIFICATION forming part of Letters Patent No. 700,285, dated May 20, 1902.

Application filed December 12, 1901. Serial No. 85,693. (No model.)

To all whom it may concern:

Be it known that I, JAMES V. ANDERSON, a citizen of the United States, residing at Clarkson, in the county of Colfax and State of Nebraska, have invented a new and useful Wire-Stretcher, of which the following is a specification.

The invention relates to improvements in wire-stretchers.

10 The object of the present invention is to improve the construction of wire-stretchers and to provide a simple, inexpensive, and efficient one of great strength and durability adapted to be readily operated and capable of continuous operation, whereby a fence-wire may be readily stretched to the desired tension without removing the wire-stretcher from it.

15 A further object of the invention is to provide a wire-stretcher of this character adapted to be readily applied to the ends of a broken fence-wire and capable of enabling the same to be drawn together and held while the terminals of the wire are being connected.

20 The invention consists in the construction and novel combination and arrangement of parts hereinafter fully described, illustrated in the accompanying drawings, and pointed out in the claims hereto appended.

25 In the drawings, Figure 1 is a perspective view of a wire-stretcher constructed in accordance with this invention. Fig. 2 is a reverse plan of the same. Fig. 3 is a transverse sectional view illustrating the construction of the boxes or casings. Fig. 4 is a detailed perspective view of one of the spring-actuated dogs.

30 Like numerals of reference designate corresponding parts in all the figures of the drawings.

40 1 designates a plate or frame provided with a bracket or support 2, within which is pivoted by a bolt 3 or other suitable fastening device an operating-lever 4, which is adapted to be oscillated to reversely reciprocate a pair of 45 boxes 5 and 6, which are provided with means for engaging a fence-wire and which are adapted to alternately stretch the same until the wire is drawn to the desired tension. The lever is fulcrumed between its ends and

50 is pivoted at opposite sides of the bracket to the adjacent ends of longitudinal bars 7 and 8, extending from the lever to the boxes or

casings. The reciprocating bars are secured to the lever by screws 9 and 10 or other suitable fastening devices, and their outer ends 55 are secured to the boxings or casings at opposite sides thereof.

The boxings or casings are arranged substantially in longitudinal alinement and are approximately rectangular in cross-section 60 and have flared outer ends, and the outer box or casing is fixed to the outer end of the reciprocating bar 7, which extends beyond the inner casing or box 6. The plate or frame 1 is provided with an arm or extension 11, having a guide 12, receiving and supporting the longer reciprocating rod or bar 7, and the box or casing 6 is provided at one side of its outer portion with a guide 13, also receiving the long bar 7. The short bar 8 is fixed to the 70 opposite side of the inner box or casing 6, and when the operating-lever is oscillated the boxes or casings are oscillated simultaneously in opposite directions. This reciprocation of the boxes or casings is adapted to effect a continuous stretching of the wire, which is quickly drawn to the desired tension.

75 Each box or casing is provided with a movable section 14, which is pivoted at one end by a screw or other suitable fastening device 80 and which is secured near its other end by a hook 15, arranged to engage a suitable headed projection of the movable wall-section and mounted on the adjacent portion of the box or casing. In applying a wire to the wire-stretcher the movable wall-sections of the boxes or casings are opened and the wires are placed in the boxes, after which the latter are closed. The wire is engaged by a pivoted dog 16, mounted on a pintle or pivot 17 and 85 having an engaging head which co-operates with a corrugated block 18 of the box or casing. The dog is provided with a corrugated engaging face, and it is held in engagement by a coiled spring 19, disposed on the pivot 90 or pintle 17 and connected with the casing or box and with the dog. Each dog is provided with a shank or handle portion 20, extending through a slot 21 of the box or casing and adapted to be readily grasped to disengage the dog from the wire.

95 The wire-stretcher may be anchored adjacent to a post by any suitable means and may then be operated to stretch a wire for 100

stapling or otherwise securing the same to a post. The plate or support is connected by a chain 22 or other suitable connection with a clamp 23, having a pivoted cam-lever 24, having a corrugated engaging face and arranged to coöperate with a flange or fixed jaw 25 for engaging a fence-wire. When it is desired to connect the ends of a broken wire, one of the ends may be held in the clamp 23 and the other may be placed in the boxes or casings, and the device can then be operated to draw the ends of the broken wire together, and it will hold the same while the terminals of the broken wire are being twisted or otherwise secured together.

It will be seen that the wire-stretcher is exceedingly simple and inexpensive in construction, that it is easily operated, and that it is capable of rapidly stretching fence-wires for securing the same to fence-posts or for connecting the ends of a broken wire.

What I claim is—

1. A wire-stretcher comprising a support, a lever fulcrumed on the support, the longitudinally-aligned boxes provided with means for engaging a fence-wire, the short and long reciprocating bars connecting the inner and outer boxes with the lever and pivoted to the

latter at opposite sides of the fulcrum thereof, and guides extending from the support and from the inner box and receiving the long reciprocating bar, substantially as described.

2. A wire-stretcher comprising the boxes arranged in alinement and each provided with a movable wall-section pivoted at one end and arranged to swing outward, a fastening device for securing the other end of the wall-section, a lever fulcrumed on the support, and bars connected with the boxes and with the lever, substantially as described.

3. A wire-stretcher comprising a support, a lever fulcrumed thereon, the longitudinally-aligned boxes having movable wall-sections, spring - actuated clamping - dogs mounted within the boxes and having shanks or handle portions extending through slots thereof, bars connecting the boxes with the lever, and a clamp connected with the support, substantially as described.

In testimony that I claim the foregoing as my own I have hereto affixed my signature in the presence of two witnesses.

JAMES V. ANDERSON.
